DESIGN FOR A SINGLE SPINDLE AUTOMATIC METAL WORKING MACHINE

Alfred E. Drissner, Cleveland, Ohio, assignor to
The National Acme Company, Cleveland, Ohio,
a corporation of Ohio

Application October 6, 1944, Serial No. 115,659

Term of patent 14 years

(Cl. D54—6)

To all whom it may concern:

Be it known that I, Alfred E. Drissner, a citizen of the United States and residing at Cleveland, in the county of Cuyahoga and State of Ohio, have invented a new, original, and ornamental Design for a Single Spindle Automatic Metal Working Machine, of which the following is a specification, reference being had to the accompanying drawing, forming part thereof.

Fig. 1 is a perspective view showing the top, one end and one side of a single spindle auto-

matic metal working machine, embodying my new design;

Fig. 2 is a perspective view of the top, end and other side thereof. The end, not shown, is substantially plain.

I claim:

The ornamental design for a single spindle automatic metal working machine, substantially as shown and described.

ALFRED E. DRISSNER.
